of Delaware

Application December 22, 1937, Serial No. 181,091

10 Claims.

(Cl. 62—5)

My invention relates to refrigeration, and more particularly to control of refrigeration apparatus. It is an object of the invention to provide an improved control for controlling the energy supply of refrigeration apparatus. More particularly, it is an object of the invention to provide an improved control device for controlling the supply of gas to refrigeration apparatus of an absorption type. I accomplish this by providing a control device which automatically controls the flow of gas to the refrigeration apparatus in response to a temperature condition and also definitely limits the maximum flow of gas to the apparatus. This control is preferably effected by a single valve member which is operated by control mechanism which is so arranged that the valve member also controls the minimum flow of gas to the refrigeration apparatus, whereby the necessity of providing a minimum by-pass 20 passage for gas around the valve member is avoided.

The invention, together with the above and other objects and advantages thereof, will be more fully understood upon reference to the following description and accompanying drawings forming a part of this specification, and of which Fig. 1 more or less diagrammatically illustrates refrigeration apparatus of an absorption type provided with a control device embodying the invention; and Fig. 2 is an enlarged vertical sectional view taken at line 2—2 of Fig. 1 to illustrate the control device more clearly.

Referring to Fig. 1, I have shown my improved control device in connection with absorption refrigeration apparatus of a uniform pressure type, generally as described in Patent No. 2,037,782 to William R. Hainsworth, in which an auxiliary pressure equalizing gas is employed. The apparatus comprises a generator 10 having a rear chamber 11 and a forward chamber 12 communicating with an upward extending stand-pipe or separator 13. The generator contains a body of absorption liquid, such as water, having a suitable refrigerant, such as ammonia, in solution therein. The generator 10 is heated by a gas burner 14 which projects its flame into the forward end of a horizontal flue 15 which extends through the generator. A suitable combustible gas is delivered from a source of supply through conduit 16, control device 17 to be described hereinafter, and conduit 18 to the burner.

The heating of generator 10 causes refrigerant vapor and absorption liquid in chamber 11 to pass through an opening 19 in the lower end of 55 the small vertical conduit 20 which constitutes

a vapor-lift and conducts refrigerant vapor and absorption liquid to the upper part of stand-pipe 13. Liberated refrigerant vapor entering stand-pipe 13 from conduit 20, and also refrigerant vapor expelled from solution in stand-pipe 13 and chamber 12, flows upward into an air-cooled condenser 21 provided with heat transfer fins 22. The refrigerant vapor is liquefied or condensed in condenser 21 and flows through a conduit 23 into the upper end of an evaporator or 10 cooling element 24 which is arranged in a thermally insulated storage space 25.

An inert gas, such as hydrogen, enters the lower end of cooling element 24 from an outer passage 26 of a gas heat exchanger 27. The liquid refrigerant evaporates and diffuses into the inert gas with consequent absorption of heat from the surroundings of cooling element 24. The resulting mixture of refrigerant and inert gas, that is, gas rich in refrigerant, flows from 20 cooling element 24 through an inner passage or conduit 28 of the gas heat exchanger which is connected at its lower end to the lower end of an absorber 29. Refrigerant vapor in the rich gas mixture is absorbed into weak absorption 25 liquid that enters the upper part of the absorber through a conduit 30. The heat liberated with such absorption of refrigerant vapor may be transferred to a cooling medium which flows through a coil 31 arranged in thermal exchange 30 relation with absorber 29.

The hydrogen or inert gas, which is practically insoluble and weak in refrigerant vapor, flows upward from absorber 29 through the outer passage 26 of the gas heat exchanger into the 35 lower end of cooling element 24. The absorption liquid flowing downward through absorber 29 becomes enriched in refrigerant vapor and flows through a conduit 32 and outer passage of a liquid heat exchanger 33 to chamber 11 of the generator 10. Refrigerant vapor and absorption liquid flow upward through conduit 20 into the upper part of stand-pipe 13, as explained above, and absorption liquid weak in refrigerant flows from chamber 12 through the inner passage or 45 conduit of liquid heat exchanger 33 and conduit 30 into the upper part of absorber 29.

The lower end of condenser 21 is connected by conduit 23, vessel 34, and conduit 35 to the gas circuit, as at the upper end of conduit 28, for 50 example, so that any inert gas which may pass through the condenser can flow to the gas circuit and not be trapped in the condenser. Any refrigerant vapor not liquefied in the condenser will flow upward in conduit 23 to displace inert 55

gas in vessel 34 and force such gas through conduit 35 into the gas circuit, thereby increasing the total pressure in the system. With such increase in pressure in the system, an adequate condensing pressure is obtained to insure condensation of refrigerant vapor in condenser 21.

In accordance with my invention the flow of gas to burner 14 is controlled by the control device 17. The control device 17 comprises a casing 36 having inlet and outlet openings 37 and 38 to which are connected conduits 16 and 18, respectively. A resilient or movable diaphragm 39 is secured at its peripheral edge between the two parts of casing 36 to form an upper chamber 40 and a lower chamber 41, and in the lower chamber 41 is provided a partition 42 having an opening to form a main passage for flow of gas from inlet 37 to outlet 38.

Within the opening in partition 42 is fixed a short sleeve member 43 which serves as a seat for a valve 44 having a stem 45 secured to diaphragm 39. The valve member 44 controls the flow of gas to burner 14 in response to a thermal element 46 which is located in chamber 40.

The thermal element 46 is in the form of an expansible diaphragm and is secured to and in communication with a hollow hub member 47. To the hub member 47 is connected one end of a tube 48 which extends through an opening in a cover plate 49 and is connected to a thermal bulb 50. The bulb 50 is arranged in thermal exchange relation with cooling element 24, as shown in Fig. 1. The hub member 47 is fixed to a resilient diaphragm 51 which is secured between the upper end of casing 36 and cover plate 49. The cover plate 49 is provided with a temperature adjustment knob 52 for adjusting the position of resilient diaphragm 51 and hence the operating position of thermal element 46.

The thermal element 46, tube 48, and bulb 50 are charged with a suitable volatile fluid and constitute an expansible fluid thermostat. The thermal element 46 expands and contracts with an increase and decrease of temperature, respectively, and these movements are utilized to regulate valve member 44 and control the flow of gas to burner 14, as will be described hereinafter.

The structure in chamber 40 for transmitting movements of thermal element 46 to valve member 44 includes a lever 53 having a knob 54 against which the thermal element 46 is adapted to bear. The lever 53 is pivoted at one end at 55 to a wall of casing 36 and the other end engages a lip or stop 56 formed at the end of a second lever 57. The lever 57 is also pivoted at 55 to the wall of casing 36 and an intermediate portion thereof bears against an upwardly extending extension 58 of valve stem 45.

The outer end of lever 57 adjacent the stop 56 is provided with a downwardly extending hollow sleeve portion 59 which is internally threaded to receive an adjustment screw 60. A coil spring 61 is disposed between the outer end of lever 53 and adjustment screw 60 to spread the levers 53 and 57 apart. By removing an outer screw 62, the inner adjustment screw 60 is accessible from the exterior of casing 36 for adjusting the tension of spring 61.

A second coil spring 63 is disposed between the outer end of lever 53 and a cup-shaped adjustment screw 64. The adjustment screw 64 is movable in a threaded opening formed in a boss 65 on casing 36. By removing an outer screw 66, the adjustment screw 64 is accessible from

the exterior of casing 36 for adjusting the tension of coil spring 63.

The operation of the control device just described is substantially as follows: When the cooling element 24 tends to rise above a desired low temperature, the volatile fluid in the expansible fluid thermostat increases in volume whereby thermal element 46 expands. With expansion of thermal element 46 the lever 53 is moved downward. Since the levers 53 and 57 are spread apart by coil spring 61, downward movement of lever 53 imparts downward movement to lever 57. The lever 57 moves the extension 58 downward against the gas pressure on the under-side of diaphragm 39, thereby increasing the opening of valve member 44. With an increase in the opening of valve member 44, gas is delivered at an increased pressure to burner 14 and additional heat is applied to generator 10 whereby the amount of cold produced by cooling element 24 is increased.

When cooling element 24 tends to fall below the desired low temperature, the volatile fluid of the expansible fluid thermostat becomes reduced in volume and thermal element 46 contracts. Due to the gas pressure on the under-side of diaphragm 39, valve member 44 moves toward its closed position with contraction of thermal element 46, the levers 53 and 57 moving upward together with valve member 44, diaphragm 39, and extension 58. With valve member 44 moved toward its closed position, gas is delivered at a reduced pressure to burner 14 and less heat is applied to generator 10 whereby the production of cold by cooling element 24 is reduced.

By controlling valve member 44 and hence the flow of gas to burner 14 in response to thermal element 46 in the manner just described, the operation of the refrigeration apparatus is effectively controlled whereby cooling element 24 is capable of maintaining the thermally insulated space 25 substantially at a desired low temperature or temperature range.

When thermal element 46 contracts and levers 53 and 57 move upward, as described above, the tension of spring 63 increases. The tension of spring 63 is adjusted to limit the extent of upward movement of levers 53 and 57 and hence limit the closing movement of valve member 44. The mechanism is preferably adjusted so that the upper limit of movement of valve member 44 is effected by spring 63 when thermal element 46 has contracted sufficiently so that it no longer bears against knob 54 of lever 53. With valve member 44 in its uppermost position, which position is dependent upon the adjusted tension of spring 63, gas is delivered to burner 14 at a minimum pressure. The rate of flow of gas to burner 14 under these conditions may be adjusted so that heat of liquid is only supplied to the refrigerant in solution in generator 10 and the refrigerant is heated to a temperature slightly below its vaporization temperature. When thermal element 46 expands and valve member 44 is moved downward from its uppermost position, gas is delivered to burner 14 at an increased pressure and additional heat is supplied to generator 10, whereby refrigerant is expelled out of solution and cold is immediately produced by cooling element 24.

During normal operation and when the valve member is moving toward and away from the valve seat formed by sleeve member 43, the spring 61 keeps the levers 53 and 57 spread apart whereby movements of thermal element 46 are effec-

tively transmitted to valve member 44. With movement of thermal element 46 the same movement is imparted to valve member 44 through the levers 53 and 57, so that no movement or sensitivity is lost.

When the valve member 44 is moved downward, the gas pressure on the discharge side of the valve member increases and an increased upward force is exerted by gas on the under-side 10 of diaphragm 39. The tension of spring 61 is so adjusted that the separating force it imparts to levers 53 and 57 above the valve member corresponds to the diaphragm load required for the desired maximum gas outlet pressure. Thus, 15 when the gas outlet pressure on the discharge side of valve member 44 and on the under-side of diaphragm 39 overcomes the tension at which spring 61 is adjusted, lever 57 moves toward lever 53 thereby permitting valve member 44 to move 20 toward its closed position. In other words, the separating force of spring 61 normally keeps the levers 53 and 57 apart and stop 56 limits the spreading of the levers a fixed distance. However, when the pressure at which gas is delivered 25 to burner 14 exceeds a predetermined maximum value, diaphragm 39 moves upward and overcomes the separating force exerted by spring 61, whereby the levers 53 and 57 are pressed together. This may occur either through a relatively large downward movement of thermal element 46 or through an increase in gas inlet 30 pressure to the control device 17.

When the levers 53 and 57 are pressed together, valve member 44 is moved upward to lower the pressure at which gas is delivered to burner 14. Irrespective of the position of thermal element 46, therefore, if the gas outlet pressure tends to exceed a predetermined maximum value, valve member 44 is moved toward 40 its closed position to reduce the flow of gas and hence definitely limit the maximum rate of flow of gas to the burner.

While I have shown and described a particular embodiment of my improved control device, I 45 do not wish to be limited to the particular arrangement set forth and illustrated in the drawings, and I intend in the following claims to cover all modifications which do not depart from the spirit and scope of the invention.

50 What is claimed is:

1. In refrigeration apparatus including a cooling element and a heat receiving part, a fluid fuel burner for heating said part, a valve for controlling flow of fluid fuel to the burner, means operated by pressure of fluid fuel on the discharge side of said valve to move said valve toward its closed position, means operative in response to a temperature condition affected by said cooling element, and means for transmitting

force resulting from movement of said temperature responsive means to cause movement of said valve toward its open position in opposition to said fuel pressure operated means, said transmitting means being effective to transmit forces only up to a predetermined maximum, whereby the pressure on the discharge side of said valve cannot exceed said maximum.

2. The combination as set forth in claim 1 in which said transmitting means is adjustable to 10 vary said maximum pressure.

3. The combination as set forth in claim 1 in which said transmitting means includes a spring.

4. The combination as set forth in claim 1 in which said transmitting means is a spring, and 15 means for adjusting the stress on said spring to vary said maximum force.

5. The combination as set forth in claim 1 in which said transmitting means includes two 20 levers, resilient means urging said levers apart, and a stop to limit separation of said levers.

6. The combination as set forth in claim 1 in which said fuel pressure operated means is a diaphragm subjected on one side to the pressure 25 of liquid fuel on the discharge side of said valve.

7. The combination as set forth in claim 1 which also includes a resilient element connected and arranged to oppose closing movement of said valve and effective to limit closing of said valve to a position at which the fuel pressure on the 30 discharge side of said valve is at a predetermined minimum.

8. The combination as set forth in claim 1 also including a spring connected and arranged to 35 oppose closing movement of said valve and effective to limit closing of said valve to a position at which the pressure on the discharge side of said valve is at a predetermined minimum, and means for adjusting said spring to vary said minimum.

9. In refrigeration apparatus including a cooling element and a heat receiving part, a fluid fuel burner for heating said part, a valve for controlling flow of fluid fuel to the burner, means responsive to pressure of fluid fuel on the discharge side of said valve urging said valve toward its closed position, means operative responsive to a temperature condition affected by said cooling element for operating said valve, and a spring connected and arranged to oppose closing movement of said valve and effective to limit closing of said valve to a position at which the fluid fuel pressure on the discharge side of said valve is at a predetermined minimum.

10. The combination as set forth in claim 9 also including means to adjust said spring to vary said minimum.

SVEN W. E. ANDERSSON.
